MACHINE FOR OPERATING UPON SHOE PARTS

Harold Warren, Swampscott, Mass., assignor to
 United Shoe Machinery Corporation, Paterson,
 N. J., a corporation of New Jersey

Application February 10, 1936, Serial No. 63,044

19 Claims. (Cl. 12—61)

This invention relates to machines for operating upon shoe parts, and is herein illustrated as embodied in a machine for operating upon counters.

5 One type of counter which has heretofore been used extensively in the manufacture of shoes is one which is provided with lips extending outwardly at the ends of the flanged portions of the counter and adapted when in position in a 10 shoe to extend along the rib of the insole.

It is an object of the present invention to provide an improved machine which is particularly adapted for forming lips on the counters of the type referred to. To this end, and as shown, 15 the invention provides a machine for operating upon counters having inturned flanges which has a support for the heel portion of the counter, a separate support for the flange at the wing portions of the counter, and a knife movable 20 heightwise of the supports for slitting the flange at opposite sides of the counter together with wipers arranged to bend the end portions of the flanges outwardly to form lips. Preferably and as illustrated, the knife and flange support are 25 adjustable together relatively to the main support so that the knife can be readily positioned to from the slits at pre-determined distances from the heel end of the counter. Preferably too, the work supports and knife are pivotally mounted 30 upon the frame of the machine and are arranged, upon a slight initial manual movement of the support about its pivot, to be moved automatically toward and then away from operative position 35 relatively to power operated means for causing operation of the knife. This construction facilitates the presentation of counters to the machine and removal of the same after an operation has been performed.

These and other features of the invention are 40 disclosed in the accompanying drawings, are described in the following detailed specification, and will be pointed out in the claims.

In the drawings,

Fig. 1 is a side elevation of a machine for operating upon counters constituting one embodiment of my invention;

Fig. 2 is a plan view of the machine;

Fig. 3 is a view partly in section showing the knife and associated mechanisms;

50 Fig. 4 represents a cross section through the driving cam and the clutch mechanism;

Fig. 5 is a detailed view partly in section illustrating the operation of the marking and punching mechanisms upon a counter; and

55 Fig. 6 is a perspective view of a counter which has been operated upon by the machine.

The machine is constructed and arranged for operation upon counters such as the counter 10, shown in Fig. 6, and is provided with instrumentalities for slitting flange portions 12 of such a

counter to form lips 14, for turning back the lips, for punching jig holes such as jig holes 16 in the flanges of the counter, and for marking the counter, as indicated by reference characters 18 and 19.

5 The machine comprises a column 20 which supports a head 22 upon which is pivotally mounted, on a shaft, a T-shaped bracket 26 adapted to carry a work support 28 and various tools for operating upon counter blanks.

10 As shown in Figs. 1 and 2, the support 28 comprises a heel shaped block which is secured to the bracket 26 by screws 30 and which is arranged to support a counter with the wing portions thereof extending forwardly and downwardly and the rear portion of the flange of the counter resting upon the upper surface of the support. The forward or wing portions of the flanges of the counters are supported by an auxiliary work support comprising a vertically extending plate 32 mounted upon a dovetailed slide 34 positioned in a groove in the upper portion of the bracket 26, the plate being secured to the slide by means of screws 36. The slide 34 is readily adjustable relatively to the support 28 for different lengths of counters by means of a thumb screw 38 which carries a collar 40 having a spiral groove 42 positioned therein and arranged to receive the end of a screw 44 which extends downwardly through an elongated slot 46 from the dovetailed slide 24. 15 By rotating the thumb screw 38 the screw 44 and consequently the slide 34 are moved inwardly or outwardly, as desired. The settings for various sizes of counters are indicated by the markings 48 on the thumb screw 38. A spring- 20 pressed detent 50 is adapted to engage with one or another of the recesses 52 upon the thumb screw to hold the slide in its adjusted position.

25 The upper end of the plate 32 has spaced extensions 54 which form guides for a knife 56 carried upon a horizontal shaft 57 which passes between the guides. The shaft 57 has a shoulder 58, Fig. 1, adapted to bear against the forward faces of the guides and the knife is forced against opposite faces of the guides by a nut 59 engaging a plate 60 on the shaft, there being a spacing member 62 between the plate and the knife. The 30 knife 56 and the plate 60 are rigidly secured together by a screw 63 and spacing collar 64. The shaft 57 is slidably mounted in a block 65 carried at the end of a plunger 66 located centrally of the support 28 and normally forced upwardly by a spring 67. Upward movement of the shaft 57, and consequently of the knife, is limited by a 35 cross-bar 68 secured to the upper ends of the extensions 54 by screws 69. Thus it is to be noted that the knife is mounted for movement heightwise of the counter support 32 but at the same time is adjustable lengthwise of the support 28 with the slide 24. When a counter is in posi- 40

45 The upper end of the plate 32 has spaced extensions 54 which form guides for a knife 56 carried upon a horizontal shaft 57 which passes between the guides. The shaft 57 has a shoulder 58, Fig. 1, adapted to bear against the forward faces of the guides and the knife is forced against opposite faces of the guides by a nut 59 engaging a plate 60 on the shaft, there being a spacing member 62 between the plate and the knife. The 50 knife 56 and the plate 60 are rigidly secured together by a screw 63 and spacing collar 64. The shaft 57 is slidably mounted in a block 65 carried at the end of a plunger 66 located centrally of the support 28 and normally forced upwardly by a spring 67. Upward movement of the shaft 57, and consequently of the knife, is limited by a 55 cross-bar 68 secured to the upper ends of the extensions 54 by screws 69. Thus it is to be noted that the knife is mounted for movement heightwise of the counter support 32 but at the same time is adjustable lengthwise of the support 28 with the slide 24. When a counter is in posi-

60

tion upon the supports 28 and 32 with the slide 34 properly adjusted for size the knife will be so located as to cut slits in the flanges of the wings of the counter at a predetermined distance from the rear end of the counter.

In order to hold the counter flanges in position during the knife stroke there are provided two holdown fingers 70 which are mounted upon shafts 71 located upon opposite sides of the work support 32 and rotatably carried by ears 72 upon the bracket 26 adjacent to the support 28. The shafts 71 also pass through ears 74 forming extensions of the slide 34. Each of the fingers 70 is slidably mounted upon a shaft 71, positioned between a pair of the ears 74 for movement with the slide 34, and is secured to the shaft 71 for rotation therewith by a key 76. The fingers 70 are provided with work-engaging extensions 78 and 80 which respectively engage the curved side portions of a counter and the flange portions of the counter located upon the work support 32. The extensions 78 project beyond the face of the support 32 to provide abutments about which the ends of the flange of the counter can be bent as will later be described. Movements of the fingers 70 are controlled by downwardly extending members 82, fixedly secured to the shafts 71, and adapted to engage cam blocks 84 located near the forward edge portion of the head 22. The fingers 70 are normally forced toward counter engaging position by a spring 86, extending through a tube 88 carried by the bracket 26, the ends of the spring being positioned on spring perches 90 on the members 82. When the bracket 26 is rotated outwardly into counter receiving position as shown in Fig. 1 the fingers 70 are moved into inoperative position by the operation of the blocks 84 in rotating the members 82 inwardly. When the bracket 26 is moved inwardly toward operative position the blocks 84 permit movement of the members 82 outwardly and the spring 86 forces the fingers 70 into engagement with the work.

In order to form the lips of the counter after the knife 56 has slit the flanges thereof I have provided two wipers 92 mounted upon a pivot 94 carried by an extension 95 of the plate 32, the wipers being normally forced toward each other by a spring 96 extending between studs 98 so that the ends of the wipers are normally held out of engagement with the flanges of a counter positioned upon the support 32. The end portions of the wipers have laterally extending work engaging portions 100 adapted to engage counter flange portions 102 (Fig. 3) of a counter 104 which lie beyond the knife after the slitting operation. In order to cause operation of the wipers there is provided a cam 105 adapted to contact with the studs 98 on the wiper arms after the knife has slit the flanges of the blank. The cam 105 is an extension of the plate 60 which is movable with the knife 56, and the cam is so positioned that after the knife in its downward movement has slit the flanges of the blank the cam will be effective to move the wipers outwardly to engage the flange portions of the counters beyond the slits and bend them upwardly.

The mechanism for marking and punching the counter will now be described. This mechanism comprises a plurality of marking disks 106 mounted in slits 108 in the block 65 (Fig. 5), the disks being carried by a spindle 110 which extends laterally of the block and is secured in position by a nut 112. The spindle 110 is provided with teeth 114 which are adapted to engage a rack 116 formed on a flattened end 117 of the shaft 57.

The disks bear number stamps which correspond to the members marked on the thumb wheel 38, and the parts are so arranged that as the slide 34 is set for a given size of counter the shaft 57 will, through the rack 116, rotate the disks 106 so that a corresponding number stamp will be in position at the lower part of the block 65 for operation upon the flange of the counter.

The means for punching jig holes in the counter flanges comprises punches 118 and 119 mounted in the block 65 upon opposite sides of the marking wheels 106. The end 120 of the punch 118 is received in a groove 122 in an enlarged portion 124 of the spindle 110 and thus serves to prevent lateral movement of the spindle.

The means for marking the center line of the counter comprises a corrugated strip of metal 125 which is positioned between the two marking disks 106 along the center line of the counter support 28.

Operation of the various tools above described upon a counter blank is accomplished by means of a power operated hammer 126 carried by a lever 128 pivoted at 130 upon a bracket 132 extending upwardly from the head 22, the lever having a roll 134 positioned in a cam track 136 of a cam 138. The cam causes a downward stroke of a hammer to engage a projection 140 on the block 65, forcing the block downwardly against the pressure of the spring 67 when the support 28 has been moved inwardly into operative position in alinement with the hammer, thus effecting simultaneously operation of the various tools carried by the block.

The cam 138 is driven by means of an electric motor 142 carried by the head 22 and having a driving pinion 144 mounted in bearings 146 and continuously in mesh with the teeth of a gear 148, the cam being operatively connected to the gear through a clutch which will now be described. The gear 148 is mounted upon a sleeve 150 which is carried by a shaft 152 mounted in bearings 154 upon opposite sides of the head 22, the gear and sleeve and shaft being secured together by a pin 156. A second sleeve 158 is slidably mounted upon the sleeve 150 and is connected with the gear 148 by pins 160 carried by the gear 148 and extending into openings 162 in the sleeve 158. The sleeve is normally forced outwardly away from the side of the gear 148 by springs 164 mounted in openings 162 and bearing upon the ends of the pins 160. Outward movement of the sleeve 158 is limited by a projection 166 on the shaft 150. The outer face of the sleeve 158 is provided with a plurality of teeth 168 adapted to engage corresponding teeth 170 in the face of a sleeve 172 loosely mounted on the sleeve 150 and bolted to the cam 138. The cam 138 which is also mounted on a shaft 152 is normally forced outwardly by a spring 174 positioned between the cam and the end of the sleeve 150 so that the teeth 170 and 168 will be held out of mesh. When the cam is forced inwardly toward the gear 148 against the pressure of the spring 174 the teeth 170 will mesh with the teeth 168, thus completing operative connection between the motor and the cam, the springs 164 providing sufficient yield to avoid clashing of the teeth as the meshing occurs.

In order that the clutch may be operated automatically upon initial manual movement of the counter support 28 about its pivot, there is a connection for moving the sleeve 172 into meshing position. This connection comprises a link 176 one end of which is mounted upon a pin 178 carried by a vertical projection 180 of the bracket 75

26 and the other end of which has a slot 182 through which the shaft 152 extends. The inner side of the link adjacent to the slot is beveled as shown at 184 so that when the link is in position to the left, as shown in Fig. 1, it will receive a correspondingly beveled collar 186 on the shaft 152 adjacent to the cam 138. In this position the clutch parts 158 and 170 will be out of engagement and the cam 138 will be stationary. However, when the link 176 is moved to the right into the position shown in Fig. 2 the collar 186 will ride up on the beveled portion 184, lateral movement of the link being prevented by engagement with the bearing 154. The 15 collar 186 thus forces the cam 138 and the clutch part 172 to the right against the pressure of the spring 174 effecting engagement of the teeth 170 and 168 in the manner previously described.

The link 176 carries a cam roll 188 arranged 20 to engage a cam track 190 in the outer face of the cam 138, the arrangement being such that after the clutch has been thrown in, the cam operates to reciprocate the link 176 with the result that the bracket 26 is moved inwardly about 25 its pivot to bring the block 140 into operative position beneath the hammer 126 and then outwardly to its original position after an operation of the tools has been performed.

In the operation of the machine, a counter is 30 placed upon the support 28 with the rear flange portions resting upon the top of the support and with the wing flange portions resting upon the auxiliary support 32, and the bracket is rotated manually through a small angle about its pivot 35 24 by exerting pressure upon the back of the counter. This movement causes rotation of the fingers 70 to grip and hold the counter upon the work supports 28 and 32, and to move the link 176 to cause inward movement of the sleeve 172 40 thereby to effect engagement of the clutch parts, after which the cam 138 automatically causes movement of the counter support about its pivot to bring the support into operative position relatively to the hammer 126. Downward movement 45 of the block 140 under action of the hammer causes the plunger 66 to move downwardly producing punching operations upon the flange of the counter, to stamp a size marking thereon, and to form an indentation to indicate the center 50 line of the counter, as shown in Fig. 6. At the same time the knife 56 is brought down to slit the forward wing portions of the flanges 12 of the counter, and after the knife passes through the flanges, the wipers 92 bend back the end 55 portions 14 of the flange. After the operation of the various tools has been effected the cam 138 causes the link to be thrown outwardly and moves the bracket 26 about its pivot into its original position and at the same time the fingers 60 70 are withdrawn so that the counter can readily be removed from the support 28.

Having described my invention, what I claim as new and desire to secure by Letters Patent of the United States is:

65 1. A machine for operating upon counters having inturned flanges comprising a support for the rear portion of a counter to be operated upon, a separate support for the ends of the flange of the counter mounted for movement relatively 70 to the first-mentioned support to determine the distance between the supports in accordance with the length of the counter, a knife movable heightwise of the separate support for slitting the 75 flange, and a member movable after the flange

has been slit to bend a portion of the flange outwardly to form a lip.

2. A machine for operating upon counters having inturned flanges, comprising a support for the flange of a counter to be operated upon, a knife mounted for movement heightwise of the support for slitting the flange at opposite sides of the counter near the ends thereof, a pair of fingers each having a flange-engaging portion for holding the counter upon the support and a laterally extending portion projecting beyond the support to engage the sides of the counter, and wiper members located between the fingers and movable to bend the flange portions at the ends of the counter outwardly to form lips. 15

3. A machine for operating upon counters having inturned flanges, comprising a support for the rear portion of a counter to be operated upon, an auxiliary support for the flange near the end portions of the counter, a knife movable heightwise of the auxiliary support for slitting the flange, and means for mounting the auxiliary support and knife for movement together relatively to the first-mentioned support. 20

4. A machine for operating upon counters comprising a work support, a plunger movable heightwise of the work support, a slide movable laterally of the work support, a knife carrier movable laterally with the slide and heightwise with the plunger, an auxiliary work support upon the slide, knife guide members carried by the slide adjacent to the auxiliary work support, a knife secured to the carrier and mounted for movement along the guide members, and means for causing movement of the plunger heightwise of the work supports. 25

5. A machine for operating upon counters comprising a work support, a spring pressed plunger movable heightwise of the support, a knife carrier supported by the plunger and mounted for movement laterally of the work support, a slide mounted for movement laterally of the work support, an auxiliary work support mounted upon the slide, a knife secured to the carrier, projections extending from the auxiliary work support 40 to act as guides for the knife, and means for slidably securing the knife carrier to the guides. 45

6. A machine for operating upon counters comprising a heel shaped work support, a slide movable laterally of the support, an auxiliary support mounted upon the slide, guide members extending from the auxiliary support, a knife mounted for movement heightwise of the auxiliary support along the guides, fingers operable to hold a counter in position upon the support 50 with the flange portions of the wings of the counter located upon the auxiliary support, means for causing an operation of the knife to slit the flange of the counter, wipers movable to bend portions of the flanges to form lips, and a cam 55 movable with the knife to cause operation of the wipers upon the work. 60

7. A machine for operating upon counters comprising a frame, a work support secured to the frame, a slide mounted upon the frame for movement laterally of the support, an auxiliary work support carried by the slide, a plunger mounted for movement heightwise of the frame, a shaft slidably mounted in the plunger, a knife secured to one end of the shaft, a connection between 65 the slide and the shaft comprising a slotted member through which the shaft passes, means for securing the shaft to the slotted member so that the knife will move laterally with the slide, and means for depressing the plunger to cause an 70 75

operation of the knife upon a counter positioned upon the work supports.

8. A machine for operating upon counters comprising a frame, a work support mounted upon the frame for supporting the rear portion of a counter, a slide carried by the frame, an auxiliary work support upon the slide for supporting the wing portions of the counter, a plunger mounted for movement heightwise of the frame and carrying a plurality of marking devices, a knife carrier mounted upon the plunger for movement with the slide, a knife mounted upon the carrier, and means for selectively locating in operative position relative to the first-mentioned work support one or another of the marking devices in accordance with the position of the knife.

9. A machine for operating upon counters comprising a frame, a main work support secured to the frame, a slide mounted upon the frame for movement laterally of the work support, an auxiliary work support mounted upon the slide, a plunger mounted for movement heightwise of the frame, a disk carried by the plunger and bearing a plurality of stamps about its periphery, a shaft extending laterally of the plunger and slidably mounted therein, a knife carried by the shaft and positioned in alinement with an end of the auxiliary work support, a rack upon one end of the shaft for rotating the disk, and means for causing lateral movement of the slide to locate the knife in operative position relatively to the main work support and to rotate the disk to present a stamp in operative position in accordance with the position of the knife.

10. A machine for operating upon counters comprising a frame, a bracket pivotally mounted upon the frame, a counter support carried by the bracket, a tool mounted upon the bracket for reciprocation heightwise thereof, and power-operated means for causing reciprocation of the tool upon movement of the bracket about its pivot.

11. A machine for operating upon counters comprising a frame, a lever mounted for oscillation relatively to the frame, a bracket pivotally mounted upon the frame, a work support on the bracket, a plunger mounted for movement heightwise of the work support, and means for moving the bracket angularly into and out of operative position with the plunger in alinement with the lever.

12. A machine for operating upon counters comprising a work support, a tool mounted for movement heightwise of the support, power operated means for forcing the tool toward the support, and means initially under manual control for automatically moving the support and tool into and out of position in operative relation to the power-operated means.

13. A machine for operating on counters comprising a frame, a work support pivotally mounted upon the frame, a knife mounted for movement heightwise of the support, means for positioning the knife laterally of the support, and automatic means for causing operation of the knife initiated by rotation of the work support about its pivot.

14. A machine for operating upon counters comprising a frame, a work support pivotally mounted on the frame, a tool carrier mounted for movement heightwise of the work support, an oscillating lever for causing an operation of the tool carrier, power means, a cam arranged to

be operated by the power means, a link operatively connecting the work support and the cam, a clutch between the cam and the power means, and means for controlling the clutch in response to a preliminary movement of the link.

5

15. A machine for operating upon counters comprising a frame, a work support pivotally mounted upon the frame, an oscillating lever, means for moving the work support into and out of operative position relatively to an end of the lever comprising a link connected to the work support, a cam for driving the link, power means, a clutch for operatively connecting the cam and the power means, and means operable upon initial movement of the work support about its pivot to cause operation of the clutch.

10

16. A machine for operating upon counters comprising a frame, a bracket pivotally mounted upon the frame, a work support carried by the bracket, a tool carrier mounted for movement heightwise of the work support, a lever for causing an operative movement of the tool carrier, and means for automatically moving the bracket about its pivot to present the tool carrier in operative position relatively to the lever.

25

17. A machine for operating upon counters comprising a frame, a work support pivotally mounted upon the frame, a tool mounted for movement heightwise of the support, power means for causing an operation of the tool upon the work, means for rotating the work support about its pivot into and out of operative relation relatively to the power means comprising a link pivotally secured to the work support, a cam for reciprocating the link, clutch members for connecting the cam to a source of power, and means operable upon manually controlled movement of the work support about its pivot for causing engagement of the clutch members.

35

18. In a machine for operating upon counters, a frame, a work support pivotally mounted upon the frame, and means for rotating the work support about its pivot comprising a link one end of which is connected to the work support, a shaft connected to a source of power, one end of the link having an elongated slot through which the shaft passes, a cam loosely mounted upon the shaft, a wedge member on the shaft and adjacent to the cam, the link having a recess adjacent to the slotted end thereof adapted to receive the wedge member, a clutch member secured to the cam, a second clutch member secured to the shaft for rotation therewith, a spring normally operative to force the cam and first-mentioned clutch member outwardly along the shaft, and a cam roll carried by the link and adapted to engage the cam.

40

19. In a machine for operating upon counters, comprising a frame, a work support pivotally mounted upon the frame, means for rotating the work support about its pivot comprising a shaft, clutch members loosely mounted upon the shaft, a beveled collar surrounding the shaft, a link one end of which is connected to the support and the other end of which has an elongated slot through which the shaft extends, the link having a recess near one end of the slot adapted to receive the collar, a spring for forcing the clutch members apart when the boss and recesses are in alinement, and a cam associated with one of the clutch members for reciprocating the link when the clutch members are in engagement.
